Inventor:

John D. Pedersen,
By his Atty, F. A. Richards.

UNITED STATES PATENT OFFICE.

JOHN D. PEDERSEN, OF JACKSON, WYOMING.

FIREARM.

Application filed July 20, 1917. Serial No. 181,764.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates to breechloading firearms, and more especially to such fire- 10 arms of the auto-loading class. While my present improvements are applicable,—by proper adaptation in size and proportions,—to auto-loading firearms of various kinds or types, they are more particularly intended 15 for use in auto-loading shoulder-arms for military use. Accordingly, and for convenience of illustration and reference, I have herein shown my present invention applied to a type of auto-loading shoulder- 20 arm which is shown and described in my copending application Serial No. 173,325, filed June 7, 1917; in said prior application my present improvements are substantially though briefly described, but being regarded 25 as a separate invention, are not claimed therein.

A principal object of this invention is to provide a simple and effective fire-control mechanism especially adapted in principle 30 and mode of action for use in shoulder-arms of said auto-loading kind, and in which the trigger-sear devices shall be rendered in- operative during the re-loading of the arm. Further objects and advantages are indicated 35 and explained in the course of the following description.

In the accompanying drawings forming a part of this specification, Fig. 1 is a 40 sectional side view of a firearm of the shoul- der arm class and comprising a primary arm combined with an auto-loading auxiliary arm provided with a fire-control mechanism made in accordance with my present invention; in this view, for convenience of illustration, the rearward and forward portions of the stock, S, also the forward part of the long main barrel, B, are omitted.

Fig. 2 is a plan view of the mechanism 50 illustrated in Fig. 1, including the entire length of the removable, or auxiliary firearm mechanism.

Fig. 3 is a sectional side view correspond- 55 ing to Fig. 1, with the exception that the bolt is shown in forward position, and that the trigger-and-sear devices of the fire-

control mechanism are disconnected as normally occurs immediately after the arm is fired.

Fig. 4 is a view similar to a portion of Fig. 3, for showing a further stage in the cycle of action of the devices comprised in the fire-control mechanism.

Fig. 5 is a cross section in line X⁵ of Fig. 3; and

Fig. 6 is a cross section in line X⁶ of Fig. 3.

Similar reference characters designate like parts in all the views.

When the complete firearm is organized 70 by combining a primary arm consisting mainly of stock and barrel, with an auxiliary arm which comprises a frame, provided with auto-loading and fire-control devices, the complete firearm has several advantages, 75 which are more fully explained in my said prior application, to which reference may be had. For instance, the relatively heavy stock and barrel,—especially when these are of the usual "military" construction and properly combined,—constitute a simple and substantial "primary" arm which serves as a base-member and has a minimum liability to injury. The light weight auto-loading auxiliary mechanism, with its small and 80 highly organized details, is much more liable to accident from both external and internal causes. Therefore, by means of the organization herein indicated, it becomes practicable to provide a soldier with two or 85 more of the auxiliary mechanisms for use in connection with one primary arm, so that in the event that one of said mechanisms becomes disabled another may be instantly substituted therefor. Thus several of the 90 auxiliary arms may be used in succession on one primary arm, and the auxiliary arms may be arranged for using, respectively, ammunition of different powers and ranges.

In the particular style of firearm to which my improved fire-control mechanism is 100 herein shown applied, the "primary arm" may be said to consist of a main barrel, as B, a stock, as S, and some suitable means for so connecting these members that they may serve as one element of a firearm which will be completed by installing on the connected stock and barrel, an auxiliary arm comprising a complete mechanism for placing and firing the cartridges, and for extracting and 105 ejecting the shells. Accordingly, it will be convenient in practice to provide the usual 110

- wooden stock of the primary arm with an adjunctive member, in the nature of a reinforcement, such for instance, as C, which,—as shown in the drawing,—may 5 have the general form of an extended bed piece, or base-plate, while serving in part as a means for connecting the barrel B and stock S. Thus the member C may constitute wholly or in part a mechanism-seat which is 10 located on or above the stock and rearward of the barrel, and is adapted for receiving thereon the frame, as F, of a firearm mechanism that is provided with a short barrel, as 6^b, forming a rearward extension of said 15 main barrel. In the present instance, the secondary frame, F, is shown having assembled therein the reciprocatable bolt, G, and the other operative details of the auxiliary firearm. 20 In practice, the primary arm should be provided, of course, with the usual sights (not herein shown), and the main barrel, B, may be held assembled on the fore-stock by the customary releasable fastenings (not 25 shown) which, being common, do not require particular description here. In order, however, to secure a rigid support and connection of the rearward end of the barrel B with the stock, I have shown the barrel- 30 end b⁵ threaded into the forward end c⁵ of said seat-plate C, so that by turning it, the barrel may be adjusted longitudinally on the stock and relative to the auxiliary arm. The barrel may be clamped in place by a 35 set-screw, as b⁶, an ordinary soft-metal shoe, as b⁷, being preferably provided for directly bearing against the barrel. The seat-plate C may be held in place by ordinary screws or fastenings of any suitable number and 40 character, as for instance, the screws c⁶ and c⁷. The primary arm in addition to having the main barrel, also constitutes a primary frame (as well as a heavy base-member) 45 for the complete firearm; similarly, the frame F constitutes a complete framework for the secondary arm. At the forward end thereof the frame F is shown provided with a short barrel, 6^b, which is preferably 50 formed integral with the frame, (Figs. 1, 3). This short barrel has formed therein the cartridge chamber 6^a, and at its forward end is preferably shaped to engage (by some suitable interlocking arrangement) 55 with the main barrel B. For this purpose, the barrel 6^b may have a tenon-like forward end, as 6^a,—preferably slightly conical as shown,—fitting closely in a socket-like space formed in the rearward end of barrel B, whereby the two barrels, form one continuous gun-barrel. Said barrels may in 60 practice, be made either with or without rifling, as may be deemed most suitable for the projectiles to be used therein. 65 The frame F, when made in the form herein illustrated, comprises the bolt-casing F² and,—depending therefrom,—a frame wall or casing, as F', within which are assembled the trigger-sear devices of the fire-control mechanism. The frame C is shown 70 having formed therein a mortise, 10, (Fig. 3), suitably shaped and proportioned for receiving said trigger-sear casing F'. This mortise should be made long enough for permitting the frame F to be retracted 75 on the primary arm to disengage the tenon 6^a from the barrel B; this movement (not herein shown) will permit said frame F to be removed by lifting it directly upward, thereby withdrawing said casing F' out of 80 the mortise. These operations are performed, of course, in a reverse manner when applying the auxiliary arm to the primary arm. For protecting the trigger, 85 4, said casing F' may be extended downwardly and shaped into a trigger-guard, as 6² located below the stock S. For releasably holding the auxiliary arm in place on the primary arm, any suitable and well-known kind of disconnectible 90 holding device may be employed, but I prefer for such purpose, a transversely-disposed bolt or locking-pin, as f⁶, (Fig. 6), provided with suitable means,—as, for instance, a lever arm, f⁷,—whereby this pin may be 95 readily removed and replaced by hand, whenever occasion may require. Said pin f⁶ is shown extending through the side walls, 3¹, 3², of said seat-plate C, and through the solidly-formed portion 3³ of the frame F, 100 thereby forming a strong and firm connection between the members F and C. A thread, 3⁴, on the pin f⁶ engages in the threaded hole at 3⁵, (Fig. 6), in said casing wall 3², whereby to reliably hold the pin 105 in place. When thus fitted, said pin-arm f⁷ constitutes a crank arm whereby said pin may be screwed into and out of place,—all 110 in an evident manner. In the frame, F, the cartridge chamber 6^a is extended rearwardly and enlarged to 115 form the breech-bolt chamber, 6^f, in which the bolt G is reciprocatable, forwardly by the power-spring 7, and rearwardly,—when a cartridge is fired,—by cartridge actuation. The bolt G is made hollow for carrying therein the firing-pin f, and is also shown provided with a short arm or connection extending through a frame-slot at 6², and there provided with the weight or momentum-block, 7^b, which also serves as a handle whereby to retract said bolt by hand to the loading position, Figs. 1, 2. When thus retracted,—by hand or otherwise,—the forward end 7¹ of the bolt G comes rearwardly 120 of the opening 6^a in the frame F, so that a cartridge will drop downward in the magazine N, and stand partially forward of the bolt G, and on the forward movement of the bolt will be pushed forward,—or 125

"placed",—into the firing position,—see Fig. 3. The magazine, N, is only partially shown, since the proper detail and arrangement thereof will be evident; it may be made of sheet metal and removably held in place by means of ribs, as 14, 14', fitting in grooves, as 15, 15', formed in the projections 6^t, 6', of the frame F.

The rearward end of said chamber 6^t may be closed by a cap, as H, removably fixed to the frame F by a screw-thread, as 6^t, or in other convenient manner. In the particular arrangement of bolt-mechanism herein shown, the cap H supports the abutment tube 8, and also serves as a stop for limiting the rearward movement (Fig. 1) of the bolt G. Similarly the part or face 8^t, of said tube 8 serves to stop the retraction of the firing-pin f before the bolt G is fully retracted, so that the point, f^t, of this pin will operate as an ejector,—as will be readily understood. For retracting the empty shell, or an un-used cartridge, from the barrel 6^t, the bolt G may be provided with an ordinary extractor, (not shown), applied and operating in accordance with a well-known method.

The power-spring, 7, may act against a face, at f^t, on the bolt G, and thus operate on the full retraction of the bolt to immediately drive the bolt forward and so load the arm. During this loading stroke of the bolt, the sear notch, or face, as 7^c, of the slide G engages the sear d on the face 3^c thereof, (Fig. 1), and thus the breech-bolt and firing pin are held in the firing position thereof.

During the forward movement of the bolt-mechanism,—which in practice will be rapidly completed by said spring 7,—the relatively heavy firing-pin f lies loosely and in a fully-retracted position in the bore 7^d of the bolt G, and will at first be held back by its own inertia and the light spring 7^e, with the collar f² of said pin resting against the shoulder at 7^t in the breech-bolt. On the bolt G stopping suddenly at the end of its forward stroke (Fig. 3), the momentum of the firing pin f compresses said pin-retracting spring 7^e and thus the point f^t of the pin is driven against the primer, and thus fires the cartridge in a manner already well-known in the art.

The sear-member is designated in a general way, by d, and in connection with devices for operating the same, constitutes a principal portion of a complete fire-control means, which, in the present instance is contained within the casing, F', extending downwardly through the mortise, 10, of the stock, so that the fire-control mechanism, or the trigger-device thereof, is manually accessible from below the gun-stock. Said intermediate sear-member may be made, in practice, of such form, length and size as

may be required to provide for the proper coaction thereof with the bolt-mechanism and the trigger-device. A preferable construction of said member d is herein shown, it being in the form substantially of a short bar having on the upper side thereof, a sear-face, as 3^c, appurtenant thereto, and having on the lower side thereof, a trigger-engaging face, as 4^c; these two faces, 3^c, 4^c, are preferably located in approximately transverse directions about as shown, the one relative to the other. By this means, the reciprocation of the member d shifts the face 4^c thereof to and from the forward and trigger-engaging position thereof in Fig. 4. Furthermore, the forward movement of the member d, from the inoperative position in Fig. 3, to the trigger-device-engaging position in Fig. 4, is effected by the transmitted force of the bolt-actuating spring 7, whereby said member d,—after the engagement of the sear-face thereof with the coacting face, as 7^c, of the bolt-mechanism member G,—is carried directly forward with said member G for a sufficient distance to bring the face 4^c thereof into said bolt-engaging position, Fig. 4. Thus the said reciprocation or forward movement of the sear-member is effected by an engagement thereof with one of the bolt-mechanism members of a plural-member bolt-mechanism,—this comprising the members G and f,—and takes place during an early part of the forward movement of such bolt-mechanism members. If, therefore, the bolt-mechanism should stick or become inoperative when at the end of its rearward stroke, the sear-member would also remain in rearward position and thus be inoperable by the trigger device.

Referring to Fig. 3, it will be noted that the point 3^c of the sear, when disengaged from the sear-engaging face 7^c to permit forward movement of the bolt G and when the sear member is released by the trigger, is held by pressure of the spring 3^b in engagement or contact with, or rides along on, the under surface of the bolt, the effect being that this spring is kept under compression during movement of the bolt, and the point 3^c of the sear is therefore in position for immediate and direct upward movement by said spring for engagement with the sear-engaging face 7^c, when the bolt member is moved to its retracted position. This arrangement also obviates the liability of breaking off the sear point 3^c by impact of the bolt G therewith when the bolt is moved rearwardly by explosion of the cartridge, as would be the case where the sear point projects into the path of the bolt and is first forced downward by the bolt and is then moved upwardly for locking engagement with bolt.

For so controlling the operation of the

sear-member that the firearm will operate as an auto-loading arm, but not as an automatic arm, I have provided a sear-retracting trigger device having a disconnecting means; this is illustrated in a preferred form and arrangement thereof in Figs. 1, 3 and 4, and the mode of operation is such that the sear-member, as *d*, is made non-retractable by the trigger excepting when both the firing pin 10 and the bolt *G* are in proper position therefor. For this purpose, as already mentioned, said sear-member is herein shown supported to have a reciprocatory movement in a direction longitudinally of the bolt movement. 15 The sear-member *d* is a one-piece member and is supported on the pin *3^a*, which passes through the slot *d'*, therefore the sear-actuating spring *3^b* which is supported and carried by the sear member and engages the 20 frame-wall or casing *F'*, operates to swing or shift the sear-member upwardly toward its position in Fig. 1, and also to force the same rearwardly, as in Fig. 3. The spring *3^b* by its engagement with the sear-member *d* provided with the slot *d'* engaging the pin *3^a* operating in the slot also affords a means for cushioning or absorbing the shock received by the sear member due to contact of the bolt-member *G* with the sear member, 25 when the bolt is moved forwardly by the spring *7* and is engaged by the sear-member for retaining the bolt-member in a retracted position. Said sear spring *3^b*, however, is normally overcome by the stronger spring *7* so that when the mechanism is in firing 30 position, (Fig. 1), the sear-member *d* will be carried forward, and so bring the hook *4^e* thereof into the trigger-engaging position shown in Figs. 1 and 4. Thus said member *d*, when arranged as here described, may be 35 said to constitute a two-motion sear device, the two movements thereof being, respectively, in transverse relative directions.

For coacting in a preferable manner with the sear *d* when this is arranged as aforesaid, the trigger, *4*, may be pivotally supported,—as by pin *4^a*,—in the casing *F'* of the frame *F*, and is shown provided with a by-pass device arranged to engage with said sear-member only when this is in its forward position, see Fig. 1. The pull-stroke of the trigger may be limited by a stop, as *4^c*, or other convenient means. The by-pass device may consist in a small lever, as *4^f*, pivoted at *4^g* to the trigger-arm *4'*, and provided at one end with the sear-engaging hook, or catch-face, *4^h*, and at the other end, *4^k*, engaging with a movement-limiting face or stop, as *6^x*, preferably appurtenant to the frame *F*. A suitable spring, as *s^e*, may be so arranged as to operate the trigger, and also normally hold said lever-end *4^k* against the stop *6^x*. For this purpose, the lever *4^f* may have an arm, *4^l*, arranged to bear upon the spring *s^e*.

On releasing the trigger *4* from its re-

tracted position, (Fig. 4),—after the sear is in its said firing position,—the by-pass hook *4^f* rides upward against and passes the sear-hook *4^h* as illustrated in Fig. 4, and thus comes to the sear-engaging position shown in Fig. 1. If, now, the trigger *4* be drawn back as in Fig. 3, the said hook *4^h* draws down the sear *d* and thereby releases the bolt-member, whereupon the sear is forced back by its spring *3^b* to the non-engaging position thereof (Fig. 3) relative to the by-pass hook *4^f* of the trigger. Thus the trigger device is for a time made inoperative, as a result of the peculiar mode of action of the two-motion sear, and this result occurs each time the arm is fired, and however rapidly the firing takes place.

Having thus described my invention, I claim:

1. In a firearm, in combination with a frame, and with a bolt-mechanism comprising a bolt member movable rearwardly by explosion of the cartridge of the firearm and movable forwardly by spring means to a retracted position and provided with a sear-engaging face, a sear member movable rearwardly and upwardly and forwardly and downwardly and provided with a point for engaging said face to retain the bolt-member in said retracted position, a spring supported and carried by the sear member and arranged for moving the same rearwardly and upwardly to engage the point thereof with said engaging face of the bolt member, and trigger means having a forwardly yielding hook engageable with the sear member for moving the same downwardly and disengageable therefrom to permit rearward and upward movement thereof.

2. In a firearm, in combination with a frame, and with a bolt-mechanism comprising a bolt member movable rearwardly by explosion of the cartridge of the firearm and movable forwardly by spring means to a retracted position and provided with a sear-engaging face, a sear member movable rearwardly and upwardly and forwardly and downwardly and provided with a point for engaging said face to retain the bolt member in said retracted position, the sear member being movable forwardly by the bolt member when the same is moved forwardly to said retracted position, a spring supported and carried by the sear member and arranged for moving the same rearwardly and upwardly to engage the point thereof with said engaging face of the bolt member, and trigger means having a forwardly yielding hook engageable with the sear member for moving the same downwardly and disengageable therefrom to permit rearward and upward movement thereof; said spring for moving the sear member rearwardly and upwardly providing means for cushioning the shock of the engagement of said bolt mem-

ber with the point of the sear member when the bolt member is moved forwardly to said retracted position.

3. In a firearm, in combination with a frame, and with a bolt-mechanism comprising a bolt member movable rearwardly by explosion of the cartridge of the firearm and movable forwardly by spring means to a retracted position and provided with a sear-engaging face, a sear member movable rearwardly and upwardly and forwardly and downwardly and provided with a point for engaging said face to retain the bolt member in said retracted position, a spring supported and carried by the sear member and arranged for moving the sear member rearwardly and upwardly to engage the point thereof with said engaging face of the bolt member, and trigger means having a forwardly yielding hook engageable with the sear member for moving the same downwardly and disengageable therefrom to permit rearward and upward movement thereof; said point of the sear member, when disengaged from the engaging face of the bolt member and when the sear member is disengaged from the trigger means, being held by said spring in contact with the under surface of the bolt member and said spring being under compression and the point of the sear member being in position for immediate and direct movement by said spring for engagement with the sear-engaging face of the bolt member when said member is moved to said retracted position.

4. In a firearm, in combination with a frame, and with a bolt-mechanism comprising a bolt member movable rearwardly by explosion of the cartridge of the firearm and movable forwardly by spring means to a retracted position and provided with a sear-engaging face, a frame-wall, a sear member provided with a point for engaging said face of the bolt member to retain the bolt member in said retracted position and provided with a slot and provided with means for engagement of trigger means therewith, a pin received in said slot for supporting the sear member for rearward and upward and forward and downward movement, a spring supported and carried by the sear member and engaging said frame-wall for moving the sear member rearwardly and upwardly, the sear member being moved forwardly when the bolt member is moved forwardly to said retracted position, and trigger means having a forwardly yielding hook engageable with the sear member for moving the same downwardly and disengageable therefrom to permit rearward and upward movement thereof.

5. In a firearm, in combination with a frame, and with a bolt-mechanism comprising a bolt-member movable rearwardly by explosion of the cartridge of the firearm and

movable forwardly by spring means to a retracted position and provided with a sear-engaging face, a frame-wall, a sear member provided with a point for engaging said face of the bolt member to retain the bolt member in said retracted position and provided with a slot and provided with means for engaging trigger means therewith, a pin received in said slot for supporting the sear member for rearward and upward and forward and downward movement, a spring supported and carried by the sear member and engaging said frame-wall for moving the sear member rearwardly and upwardly, and trigger means having a forwardly yielding hook engageable with the sear member for moving the same downwardly and disengageable therefrom to permit rearward and upward movement thereof; said point of the sear member, when disengaged from the engaging face of the bolt member and when the sear member is disengaged from the trigger means, being held by said spring in contact with the under surface of the bolt member, and said spring being under compression and the point of the sear member being in position for immediate and direct movement by said spring for engagement with the sear-engaging face of the bolt member when said member is moved to said retracted position.

6. In a firearm, in combination with a frame, and with a bolt-mechanism comprising a bolt member movable rearwardly by explosion of the cartridge of the firearm and movable forwardly by spring means to a retracted position and provided with a sear-engaging face, a frame wall, a sear-member provided with a point for engaging said face to retain the bolt-member in said retracted position when the bolt-member is moved forwardly and provided with a hook and provided with a slot, a guide-pin engaging in said slot for supporting the sear-member and permitting rearward and upward and forward and downward movement of the sear-member, a spring supported and carried by the sear member and engaging said frame-wall for moving the sear-member rearwardly and upwardly to engage the point thereof with said engaging face of the bolt-member, and a trigger device comprising a trigger arm and comprising a by-pass device consisting of a lever pivoted to said trigger arm provided at one end with a hook for engaging said hook of the sear-member, said lever engaging at the other end thereof a movement-limiting face.

7. In a firearm, in combination with a frame, and with a bolt-mechanism comprising a bolt member movable rearwardly by explosion of the cartridge of the firearm and movable forwardly by spring means to a retracted position and provided with a sear-engaging face a frame wall, a sear-member

provided with a point for engaging said face of the bolt-member to retain the bolt-member in said retracted position when the bolt-member is moved forwardly and provided with a hook and provided with a slot, a guide-pin engaging in said slot for supporting the sear-member and permitting rearward and upward and forward and downward movement of the sear-member, a spring supported and carried by the sear member and engaging said frame-wall for moving the sear-member rearwardly and upwardly to engage the point thereof with said engaging-face of the bolt-member, and a trigger device comprising a trigger arm and

comprising a by-pass device consisting of a lever pivoted to said trigger arm having a spring-engaging arm, said lever being provided at one end with a hook for engaging said hook of the sear-member, said lever at the other end thereof engaging a movement-limiting face, and a spring engaging said arm of the lever for operating the trigger and for normally holding the end of said lever against said movement-limiting face. 20
